UNITED STATES PATENT OFFICE.

JOHN ELLENBECKER, OF PORT WASHINGTON, WISCONSIN.

REVOLVING CHAIR.

SPECIFICATION forming part of Letters Patent No. 655,211, dated August 7, 1900.

Application filed January 19, 1900. Serial No. 1,970. (No model.)

To all whom it may concern:

Be it known that I, JOHN ELLENBECKER, of Port Washington, in the county of Ozaukee and State of Wisconsin, have invented a new 5 and useful Improvement in Revolving Chairs, of which the following is a description, reference being had to the accompanying drawings, which are a part of this specification.

My invention has relation to improvements 10 in chairs of the class known as "revolving" chairs.

One of the objects of the invention is an improved construction wherein mechanism is employed whereby the chair may be freely 15 revolved when desired without changing the height of the chair-seat and in connection therewith a positive and simple improved means for raising and lowering the chair-seat when desired.

With the above primary and other incidental objects in view the invention consists 20 of the devices and parts or their equivalents, as hereinafter set forth.

In the accompanying drawings, Figure 1 is 25 an elevation of the invention, parts being shown in section and parts broken away. Fig. 2 is an elevation of the upper portion of the device at right angles to Fig. 1, parts being in section. Fig. 3 is an inverted plan view. Fig. 4 is a horizontal section on the line 4-4 of 30 Fig. 1 looking upwardly, one of the legs being shown as detached; and Fig. 5 is an elevation of a modified form.

Referring to the drawings, the numeral 6 35 indicates the hub of the chair-iron, said hub having an enlarged upper end, forming a ball-bearing pocket 7 for the reception of anti-friction-balls 8. The hub is also provided at its upper end with an outwardly-extending 40 flange 9.

The numerals 10 indicate the improved form of legs adopted by me. Each of these legs is of cast metal, and each is preferably provided with top and bottom edge flanges 11 45 and 12, respectively. The inner end of each leg is formed with a segment or curved flange 12'. The lower end of each segment is widened or thickened, as indicated by the numeral 13, so as to fit snugly against the hub 6, and the upper end of each segment fits against 50 the enlarged upper end of the hub. When all the legs are in position, with the segments

fitted to the hub, said segments form a complete cylinder around said hub. Just back of the segment each leg is formed with vertical and elongated concavities or half-tubular portions 14, which are in vertical alignment, but with the bulges or concavities alternating in direction. These alternating half-tubular portions therefore form a complete vertical passage for bolts 15, which bolts pass through openings in the top flange 9, thence through the openings formed by the alternating concavities, and thence through a bottom plate 16. The lower ends of the 65 bolts are threaded to receive nuts 17. These nuts are preferably disposed between ridges 18 on the under side of the plate 16, said ridges holding the nuts against turning. The upper ends of the bolts are provided with 70 notched heads, which are adapted to be engaged by a screw-driver. When a bolt is turned, the head at the upper end thereof is brought into firm engagement with the flange 9, and the nut 17 is turned tightly against the 75 under side of the plate 16.

The improved form of legs having the particular construction described is capable of being cast in one casting, so that the several constituent elements thereof, as mentioned, 80 will be formed in one integral part with the legs when the casting is removed from the sand. In this manner I am enabled to provide a strong and enduring metallic leg which can be manufactured at a minimum of expense. 85

The flange 11 at the upper edge of each leg passes between straight ridges 19 on the under side of the top flange 9, and these ridges therefore serve to assist the bolts in preventing lateral displacement of the upper ends 90 of the legs. The ridges 19 are connected by curved ridges 20, which receive back thereof the upper ends of the segments 12', and thereby assist the bolts in preventing outward displacement of the legs. The upper side of the 95 plate 16 is also provided with straight ridges 21, which receive between them the flanges 12 at the under edges of the legs, and therefore serve the same function as the ridges 19. The ridges 21 are likewise connected by 100 curved ridges 22, which receive back of them the lower ends of the segments 12', and thereby serve the same function as the curved ridges 20.

In order to prevent accidental twisting or turning of the lower end of the hub 6, I provide the same with a spline or groove 23, which is adapted to be engaged by a feather 24, projecting from the bottom plate 16, and thereby locking the two parts firmly together.

Fitting within the hub 6 is a sleeve 25. The upper end of this sleeve terminates short of the upper end of the hub, and the upper 10 extremity of said sleeve is flanged, as indicated by the numeral 26. This flange confines the antifriction-balls 8 between its under side and the bottom of the ball-bearing pocket 7. The sleeve is provided with a 15 smooth bore, and fitting revolvably therein is a screw-threaded spindle 27. The spindle is provided with a vertical groove 28, which receives a lug 29, projecting from the sleeve. By this means the sleeve and spindle are 20 locked to revolve together. The spindle is pendent from a spider 30, which, as is usual in this class of devices, is secured to the under side of the chair-seat. The spindle is engaged by a nut 31, which nut at its upper end 25 is formed or provided with a rigid wheel 32. As shown in Figs. 1 and 2, this wheel is in the form of a toothed wheel. The lower end of the nut fits freely in the upper enlarged end of the hub above the flange 26 of the sleeve 30 25, and this lower end of the nut is enlarged or flanged, as indicated by the numeral 33, said enlarged or flanged end having frictional contact with the upper side of the flange 26. The frictional contact is preferably reduced 35 to the minimum by providing the under side of the flanged end of the nut with an annular bead 34. Some means should be provided for preventing the nut when independently turned from working upwardly. As a preferable means I extend the hub 6 slightly 40 above the flange 9 of said hub and curve this extension inwardly, as indicated by the numeral 35. In this curved extension is fitted a spring-ring 36. It is obvious that when the 45 nut is turned independently of the spindle it is impossible for said nut to work upwardly, owing to its contact with said spring-ring.

The toothed wheel 32 at the upper end of the nut is engaged by another toothed wheel 50 37, said wheel 37 being preferably in the form of a lantern-wheel, with its top and bottom flanges extending over the top and bottom edges of the wheel 32 in order to keep the two wheels in proper engagement. The 55 wheel 37 is carried rigidly at the lower end of a spindle 38, which spindle is mounted in a bearing 39. The spindle 38 is surrounded by a tubular shaft 40, and this tubular shaft 40 is mounted at its upper end in a bearing 60 41. The upper end of shaft 40 extends slightly above the bearing 41 and carries rigidly a beveled gear-wheel 42, which wheel is in mesh with another beveled gear-wheel 43, carried on a horizontal shaft 44, said shaft 65 44 provided at its outer extremity with a hand-wheel 45 for convenience in turning the same. The tubular shaft 40 is provided with an

elongated slot 46, which receives a pin or stud 47, projecting from the spindle 38.

The above being a description of the different parts of my invention, its operation will now be described. When the chair-seat is turned, the spider travels around with the chair-seat and the screw-threaded spindle 27, the sleeve 25, and the nut 31, engaging the 70 spindle, all rotate together. If it is desired to raise or lower the chair-seat, the hand-wheel 45 is turned, and this turning through the meshing of the bevel-gear 43 with the bevel-gear 42 will cause the tubular shaft 40 75 to be rotated, and the rotation of said tubular shaft is communicated to the spindle 38 by reason of the engagement of the pin 47 with the elongated slot 46 of said tubular shaft 40. As the spindle 36 is thus rotated 80 the toothed wheel 37 is necessarily rotated therewith, and by reason of the fact that said toothed wheel engages the toothed wheel 32 at the upper end of the nut 31 said nut is necessarily rotated. Inasmuch as the nut 90 cannot move vertically, its rotation will necessarily raise or lower the screw-threaded spindle in accordance with the direction of the turning of the nut. When the chair-seat is revolved for the purpose of freely turning 95 without any change in the adjustment, the weight of the chair iron and seat is carried by the antifriction-balls, and friction is reduced to the minimum by reason of the provision of said antifriction-balls.

100

In Fig. 5 of the drawings I show a modified form of construction wherein the toothed wheel 32 and the meshing wheel 37 and its related parts are dispensed with. In lieu of the toothed wheel 32 I provide a hand-wheel 105 48, which of course when turned by hand will cause the raising or lowering of the screw-threaded spindle. This modified form renders it necessary for a person to leave the chair-seat and then stoop down in order to 110 obtain access to the hand-wheel 48. In the construction shown in Figs. 1 and 2, however, a person can readily grasp the hand-wheel 45 and turn the same, so as to secure a vertical 115 adjustment of the height of the chair-seat without the necessity of leaving the chair-seat.

By arranging the antifriction-balls 8 as shown—viz., disposed between the under side of the flange 26 and the bottom of the pocket 120 7—when the chair-seat is revolved there is no part of the nut which comes into frictional contact with another revolving part, and hence there is no danger of the screw-threaded spindle working either upwardly or downwardly. If the sleeve 25 and its flange 28 were omitted and the antifriction-balls 6 placed between the flanged lower end of the nut and the bottom of the pocket 7, it is obvious that the friction of the nut in revolving 125 around on the antifriction-balls might be sufficient to cause an independent rotation of the nut, and hence an up-and-down movement of the screw-threaded spindle at a time.

130

when it was not desired that there should be any vertical adjustment. The sleeve 25, therefore, is preferably and advisably employed in my construction. The slot 46 in the tubular shaft 40, engaged by the stud or pin 47, allows the bevel-gears to be always in mesh, no matter what may be the vertical adjustment of the chair.

Another feature of my invention to which I would call attention is the manner in which the bearings 39 and 41 are carried. Referring to this feature, the numeral 49 indicates a yoke the side arms of which are connected by two cross-bars 50 and 51, respectively. The bearing 39 is rigid with the cross-bar 50 and the bearing 41 rigid with the cross-bar 51. The shaft 44 is journaled in the upper extremities of the side arms of the yoke 49. The spider 30 is provided with the depending arms 52 52, which are provided with eyes for the passage therethrough of the pivot-pin 53 of the spider. The side arms of the yoke 49 are adapted to fit between the side arms 52 of the spider, and said side arms of the yoke are provided with projecting lugs 54, having eyes therethrough which are in register with the eyes of the arms 52, and hence provide for the passage therethrough of the pivot-pin 53. The head of the spindle 27 is also provided with a cross-bar 55, which is adjacent to the cross-bar 50. This cross-bar 55 is provided with upwardly-extending arms 56 56, which are adjacent to the inner sides of the depending arms 52 52. These arms 56 are also provided with eyes through which the pivot-pin 53 passes. Each arm 56 is further provided with a lateral shoulder 57, (see Fig. 5,) which forms a stop against which the edge of the arm 52 contacts, and thereby limits the tilting of the chair in one direction. By the provision of this construction by simply removing the pivot-pin 53 the entire yoke 49 can be disconnected, and hence the screw-threaded spindle 27 readily and quickly removed from the hub.

What I claim as my invention is—

1. The combination of a hub having an enlarged upper end forming an interior shoulder below said upper end, a loose sleeve in the hub, said sleeve having a smooth bore, and said sleeve having at its upper end a flange, said flanged upper end terminating below the upper end of the hub, antifriction-balls confined between the flange of the sleeve and the interior shoulder of the hub, a screw-threaded spindle extending into the smooth bore of the sleeve, means for locking the sleeve and spindle together, but allowing vertical movement of the latter, a nut on the screw-threaded spindle and supported by the flange at the upper end of the sleeve, and means for holding said nut against vertical movement on the spindle.

2. The combination, of a hub, a loose sleeve in the hub and having a smooth bore, a screw-threaded spindle extending into the smooth bore of the sleeve, means for locking the sleeve and spindle together, but allowing vertical movement of the latter, a nut on the screw-threaded spindle and supported by the sleeve, said nut formed or provided with a rigid toothed wheel, another toothed wheel engaging the toothed wheel of the nut, means for rotating said other toothed wheel, and means for holding the nut against vertical movement on the spindle.

3. The combination, of a hub, a loose sleeve in the hub and having a smooth bore, a screw-threaded spindle extending into the smooth bore of the sleeve, means for locking the sleeve and spindle together, but allowing vertical movement of the latter, a nut on the screw-threaded spindle and supported by the sleeve, said nut formed or provided with a rigid toothed wheel, shafts or spindles telescopically or slidingly fitted together so as to be extensible, but adapted to be rotated together, one of said shafts or spindles carrying a toothed wheel engaging the toothed wheel of the nut, and the other of said shafts or spindles carrying a gear-wheel, another shaft carrying a gear-wheel in mesh with the first-referred-to gear-wheel, means for turning said shaft, and means for holding the nut against vertical movement on the spindle.

4. The combination, of a hub, a spindle fitting therein, said spindle provided at its upper end with a cross-head having upwardly-extending arms therefrom, the said arms having eyes therethrough, a nut on the spindle, said nut provided with a toothed wheel, a spider, said spider provided with downwardly-extending arms having eyes therethrough registering with the eyes of the upwardly-extending arms, a yoke, the side arms thereof having connecting cross-bars formed with bearings, and said side arms of the yoke also provided with eyes registering with the eyes of the arms of the spider and with the eyes of the upwardly-extending arms, a pivot-pin passing through the registering eyes, shafts or spindles journaled in the respective bearings and telescopically or slidingly fitted each to the other and revolvably connected together, a toothed wheel carried by one of said shafts and meshing with the toothed wheel of the nut, a gear-wheel carried by the other shaft, and another shaft journaled in the side arms of the yoke and carrying a gear-wheel meshing with the other gear-wheel.

In testimony whereof I affix my signature in presence of two witnesses.

JOHN ELLENBECKER.
